(57) **CLAIM**

The ornamental design for a gun holster, as shown.

DESCRIPTION

FIG. 1 is a perspective view of a first embodiment of a gun holster showing my new design;

FIG. 2 is a first elevational side view in accordance with the first embodiment thereof;

FIG. 3 is a second elevational side view in accordance with the first embodiment thereof;

FIG. 4 is a top view in accordance with the first embodiment thereof;

FIG. 5 is a bottom view in accordance with the first embodiment thereof;

FIG. 6 is a front view in accordance with the first embodiment thereof;

FIG. 7 is a rear view in accordance with the first embodiment thereof;

FIG. 8 is a perspective view of a second embodiment of a gun holster showing my new design;

FIG. 9 is a first elevational side view in accordance with the second embodiment thereof;

FIG. 10 is a second elevational side view in accordance with the second embodiment thereof;

FIG. 11 is a top view in accordance with the second embodiment thereof;

FIG. 12 is a bottom view in accordance with the second embodiment thereof;

FIG. 13 is a front view in accordance with the second embodiment thereof;

FIG. 14 is a rear view in accordance with the second embodiment thereof;

FIG. 15 is a perspective view of a third embodiment of a gun holster showing my new design;

FIG. 16 is a first elevational side view in accordance with the third embodiment thereof;

FIG. 17 is a second elevational side view in accordance with the third embodiment thereof;

FIG. 18 is a top view in accordance with the third embodiment thereof;

FIG. 19 is a bottom view in accordance with the third embodiment thereof;

FIG. 20 is a front view in accordance with the third embodiment thereof;

FIG. 21 is a rear view in accordance with the third embodiment thereof;

FIG. 22 is a perspective view of a fourth embodiment of a gun holster showing my new design;

FIG. 23 is a first elevational side view in accordance with the fourth embodiment thereof;

FIG. 24 is a second elevational side view in accordance with the fourth embodiment thereof;

FIG. 25 is a top view in accordance with the fourth embodiment thereof;

FIG. 26 is a bottom view in accordance with the fourth embodiment thereof;

FIG. 27 is a front view in accordance with the fourth embodiment thereof;

FIG. 28 is a rear view in accordance with the fourth embodiment thereof;

FIG. 29 is a perspective view of a fifth embodiment of a gun holster showing my new design;

FIG. 30 is a first elevational side view in accordance with the fifth embodiment thereof;

FIG. 31 is a second elevational side view in accordance with the fifth embodiment thereof;

FIG. 32 is a top view in accordance with the fifth embodiment thereof;

FIG. 33 is a bottom view in accordance with the fifth embodiment thereof;

FIG. 34 is a front view in accordance with the fifth embodiment thereof;

FIG. 35 is a rear view in accordance with the fifth embodiment thereof;

FIG. 36 is a perspective view of a sixth embodiment of a gun holster showing my new design;

FIG. 37 is a first elevational side view in accordance with the sixth embodiment thereof;

FIG. 38 is a second elevational side view in accordance with the sixth embodiment thereof;

FIG. 39 is a top view in accordance with the sixth embodiment thereof;

FIG. 40 is a bottom view in accordance with the sixth embodiment thereof;

FIG. 41 is a front view in accordance with the sixth embodiment thereof;

FIG. 42 is a rear view in accordance with the sixth embodiment thereof;

FIG. 43 is a perspective view of a seventh embodiment of a gun holster showing my new design;

FIG. 44 is a first elevational side view in accordance with the seventh embodiment thereof;

FIG. 45 is a second elevational side view in accordance with the seventh embodiment thereof;

FIG. 46 is a top view in accordance with the seventh embodiment thereof;

FIG. 47 is a bottom view in accordance with the seventh embodiment thereof;

FIG. 48 is a front view in accordance with the seventh embodiment thereof;

FIG. 49 is a rear view in accordance with the seventh embodiment thereof;

FIG. 50 is a perspective view of an eighth embodiment of a gun holster showing my new design;

FIG. 51 is a first elevational side view in accordance with the eighth embodiment thereof;

FIG. 52 is a second elevational side view in accordance with the eighth embodiment thereof;

FIG. 53 is a top view in accordance with the eighth embodiment thereof;

FIG. 54 is a bottom view in accordance with the eighth embodiment thereof;

FIG. 55 is a front view in accordance with the eighth embodiment thereof;

FIG. 56 is a rear view in accordance with the eighth embodiment thereof;

FIG. 57 is a perspective view of a ninth embodiment of a gun holster showing my new design;

FIG. 58 is a first elevational side view in accordance with the ninth embodiment thereof;

FIG. 59 is a second elevational side view in accordance with the ninth embodiment thereof;

FIG. 60 is a top view in accordance with the ninth embodiment thereof;

FIG. 61 is a bottom view in accordance with the ninth embodiment thereof;

FIG. 62 is a front view in accordance with the ninth embodiment thereof;

FIG. 63 is a rear view in accordance with the ninth embodiment thereof;

FIG. 64 is a perspective view of a tenth embodiment of a gun holster showing my new design;

FIG. 65 is a first elevational side view in accordance with the tenth embodiment thereof;

FIG. 66 is a second elevational side view in accordance with the tenth embodiment thereof;

FIG. 67 is a top view in accordance with the tenth embodiment thereof;

FIG. 68 is a bottom view in accordance with the tenth embodiment thereof;

FIG. 69 is a front view in accordance with the tenth embodiment thereof; and,

FIG. 70 is a rear view in accordance with the tenth embodiment thereof.
